Primary Examiner—Melanie H Tung*(74) Attorney, Agent, or Firm*—Hamilton, Brook, Smith & Reynolds, P.C.(57) **CLAIM**

The ornamental design for a user interface for file system for a computer display, as shown and described.

DESCRIPTION

The single FIGURE is a front view of a user interface for a file system for a computer display.

The broken line showing of the computer display is for illustrative purposes only and forms no part of the claimed design.
